UNITED STATES PATENT OFFICE

2,475,352

TROLLEY WIRE TAP

John F. Conrad, Ebensburg, Pa.

Application April 19, 1948, Serial No. 21,953

2 Claims. (Cl. 200—115.5)

1

My invention relates to trolley wire taps for connecting mobile electric machines to trolley wires and is designed as an improvement over the tap forming the subject matter of my co-pending application, Serial No. 697,940, filed September 19, 1946.

By way of premise, the tap of my co-pending application, supra, is of the fused type with a tubular handle forming fuse casing, a trolley wire engaging hook and a hand guard at one end of the casing, a terminal connection between said hook and fuse including a shunted spring connector, a conductor cable at the other end of the casing, and a terminal connection between said cable and fuse.

Among the important objects of my instant invention is to provide in such taps a better hook connection capable of withstanding greater tensile strain, a safer, more secure, and longer lasting mounting for the hand guard, an improved shunted spring connector obviating loss of the same when changing fuses and providing for a better electrical connection between the fuse and hook, and a connection between the conductor cable and fuse adapted to hold against unusually heavy and sudden strain and easily and quickly assembled to assure good electrical connection between the cable and fuse.

Other and subordinate objects, within the purview of my invention, together with the precise nature of my improvements, will be readily understood when the succeeding description and claims are read with reference to the drawing accompanying and forming part of this specification.

In said drawing:

Figure 1 is a view in longitudinal section illustrating my improved trolley wire tap in a preferred embodiment thereof;

Figure 2 is a view in perspective of the shunted spring connector drawn to a larger scale;

Figure 3 is a view in longitudinal section through the same taken on the line 3—3 of Figure 2;

Figure 4 is a composite view in perspective of the screw plug, hand guard, bushing, coupling sleeve, washer and pin for the coupling sleeve, all disassembled;

Figure 5 is a view in perspective of the socket member forming part of the connection between the conductor cable and fuse;

Figure 6 is a fragmentary view in longitudinal section of a modified embodiment of my invention;

Figure 7 is a similar view of another modified embodiment.

2

Referring now to the drawing by numerals, and first to Figures 1 to 5 illustrating the preferred embodiment of my invention, 1 designates the tubular, handle forming, casing for the fuse 2, and which, in the present instance, is preferably formed of Micarta, although other similar insulation material may be used. The casing 1 is provided with a smooth uniform diameter bore 3.

The connection between the trolley wire engaging hook, designated 4, and the fuse 2 comprises a screw plug 5 of brass, having an inner end, cup-like, cylindrical socket 6 longitudinally slit, as at 7, to form resilient gripping fingers 8 on said socket, and which is sleeved for a short distance over one end cap 9 of the fuse 2 with said fingers 8 gripping said cap. The screw plug 5 further includes an axial outer end stud 10 on the end of the socket 6 opposite the fuse fitting end and which is provided with a threaded end 11.

The socket 6 is threaded externally, with the exception of the gripping fingers 8, and turned into a relatively shorter, internally threaded, brass bushing 12 forming an insert in one end of the casing flush with the outer edge of said bushing 12 and said end of the casing 1, for a particular purpose presently seen.

The bushing 12 is externally knurled, as at 13, slightly oversize, with respect to the bore 3 of the casing 1, and is forced into said bore 3 under heavy pressure, with a bonding cement, not shown, applied to the same externally whereby, after the cement has set, said bushing 12 is firmly fixed in and bonded with said bore 3 against pulling loose under exceptionally heavy strains. A pair of diametrically opposite studs 14 are provided on the end of the socket 5 opposite the fuse fitting end and at opposite sides of the stud 10, for a purpose presently seen.

An internally threaded, externally knurled, coupling sleeve 15 turned onto a threaded shank 16 on the trolley wire engaging hook 4 and also turned onto the terminal end 11 of the stud 10 connects said shank to said stud 10 in axial alignment therewith, whereby said hook 4 is detachably connected to the screw plug 5. A radial locking pin 17 in the coupling sleeve 15 locks said sleeve to said stud 10. The coupling sleeve 15 is formed with a circumferential base flange 18 for a particular purpose presently apparent.

The hand guard 19 is of the usual disk-like, washer shape, but is formed of a flame-resistant, non-breakable material, impervious to moisture absorption and inherently a good insulator, for

instance, butadiene synthetic rubber. The hand guard 19 is fitted tight around the stud 10 and clamped against the stud equipped end of the socket 6 and against the bushing 12, also the adjacent end of the casing 1, by the coupling sleeve 15 and a brass washer 20 interposed between said guard and the base flange 18 of said sleeve 15. In this position thereof, said guard 19 is impaled on the studs 14 and securely held shunted against rotary play.

The shunted spring connector comprises a pair of brass washers 21 connected in the axis thereof by a flexible conductor in the form of a short length of copper cable 22. The washers 21 are provided with axial recesses 23 in outer sides thereof in which the strands of the cable 22 are mushroomed and anchored by solder 24. The usual coil spring 25 of brass surrounds the cable 22 and is interposed between the washers 21 to spread the same apart.

The washers 21 fit loosely in the socket 6 with one fitting flat against the bottom of said socket and the other similarly fitting against the cap 9 of the fuse 2, and the coil spring 25 is slightly compressed so that the washers exert pressure against the bottom of the socket 6 and the fuse 2, for a reason presently seen, and the cable 22 electrically connects said fuse with the bottom of said socket 6.

A particular feature of my invention is means for frictionally locking the described shunted spring connector in the socket 6 comprising the following. Peripheral grooves 26 are provided in the washers 21 and in which are seated transversely split expanding rings 27 of copper, for frictionally engaging the circumferential wall of the socket 6 to frictionally lock said connector in said socket against falling out during the operation of replacing the fuse 2.

As will be seen, the described shunted spring connector establishes good electrical contact between the fuse 2 and the screw plug 5, which is to say, the socket 6 of said plug, and which is in good electrical connection with the trolley wire engaging hook 4, and the current is shunted from the fuse 2 to the screw plug 5 by way of the cable 22 so that the coil spring 25 is not used as a primary conductor and the life of the same will not be impaired by the action of heat.

Coming now to the terminal connection for the conductor cable designated 28, the sheath 29 of the said cable 28 has one end thereof extended into and fitted in an annular plug 30 of the same material as the casing 1, preferably, but which may be of the same material as the hand guard 19, said plug 30 being tightly fitted, with a drive fit, in the end of the casing 1 opposite the hook equipped end with a coating 31 thereon of glue impregnated with emery or other sand to form a substantially permanent, indestructible bond between said plug and said casing 1. The strands 33 of the cable 28 extend through a tubular brass nut 32 in the casing 1 having a wrench hold head 34 seating flat against said plug 30.

A cylindrical brass socket member 35 with an internally threaded end 36 and a flat bottomed opposite socket end 37 longitudinally slit, as at 38, has said end 36 thereof turned down on the nut 32 with the cap on the other end of the fuse 2 seated in said socket end 37 and frictionally gripped thereby through the slit structure thereof which is rendered resilient by the slits 38. As will be understood, the spring 25 acts as a compression member against the fuse 2, firmly seating said fuse in the socket end 37.

A brass ring 39 in the socket end 36 surrounds the strands 33 and said strands are mushroomed, or bent, thereover, as at 40, and clamped by the socket member 35 against said ring with the ring clamped against the nut 32. The nut 32 and socket member 35 are dimensioned to pass through the bushing 12 for assembling, or disassembling, the tap. Flat wrench holds are provided on the said end 36 of the socket member 35 for turning the same off and on the nut 32 with a wrench.

As will be manifest, the coupling sleeve 15 forms a lock-nut for the trolley wire engaging hook 4 whereby said hook is locked to the stud 10 and hence to the screw plug 5, so that said hook 4, sleeve 15 and guard 19 and screw plug 5 may be detached with the shunted spring connector frictionally held in said plug, all these parts being detachable as a unit by merely turning the screw plug 5 out of the bushing 12 using the hook 4 as a hand grip. Conversely, these parts may be attached as a unit by merely turning the screw plug, that is, the socket 6 of said plug 5 into said bushing 12. Also, the socket member 35 and the nut 32 may be moved out of the same end of the casing 1 by pulling the conductor cable 28 through the plug 30, and without detaching the bushing 12.

In the modified embodiment of my invention shown in Figure 6, an optional form of plug for the conductor cable end of the fuse casing 1 is shown as comprising an annular plug section 39 of butadiene synthetic rubber, but otherwise like the plug 30 and similarly secured in the end of the casing 1, said plug further comprising a brass, annular, inner plug section 42, on the inner side of the plug section 39, against which the nut 41, corresponding to nut 32, seats flat. The plug sections 39, 42 are suitably sized for extension of the conductor cable 45 therethrough and the annular plug section 42 is knurled, as at 46, and oversized as regards the size of the casing 1 internally to be imbedded in the wall of said casing when pressed into the same. In this embodiment of the invention, the plug section 45 serves as an insulator, augments the plug section 40 against strain caused by heavy pull on the conductor cable 45, and relieves strain on the cable insulating sheath 46 when said cable is pulled laterally. A coating of phenol glue, not shown, may be applied to the plug section 40 for additionally bonding the same to said casing.

In the modified embodiment of my invention shown in Figure 7, another optional form of plug for the terminal connection between the conductor cable 47 and the casing 1 is shown as comprising a stepped outer plug section 48 of the same material as the plug section 39 and similarly secured in the casing 1, with the smaller part on the inside and capped by an annular, brass, bell shaped plug section 49 peripherally knurled, as at 50, and oversized, for the same purpose as the plug section 40, and also notched, as at 51, to form resilient out-turned, circumferential sections 52 thereon for biting into the wall of the casing 1. A coating of phenolic glue, not shown, may be applied to the plug section 49 in assembling to additionally bond the same with said casing 1.

As will be seen, the modified embodiment of plugs shown in Figures 6 and 7 are particularly designed to resist heavy pull against the same and sudden jerking by the conductor cable.

The foregoing will, it is believed, suffice to impart a clear understanding of my invention, without further explanation. Manifestly, the

invention, as described, is susceptible of modification, without departing from the inventive concept, and right is herein reserved to such modifications as fall within the scope of the appended claims.

Having described the invention what is claimed as new is:

1. In a trolley wire tap, a tubular handle forming fuse casing of insulation material, a conductive bushing fixed in one end of said casing and internally threaded, a conductive screw plug having an externally threaded inner end socket turned into said bushing and adapted to fit over one end of a fuse in said casing, said plug having an axial outer end stud on the other end of the socket, a hand guard of insulation fitted over said stud, a conductive trolley wire engaging hook having a shank aligned with said stud, a coupling sleeve threaded onto said stud and shank for coupling the same together in engaging locked relation and clamping said guard against said socket, and a conductor in said socket electrically connecting the same and said fuse and frictionally locked therein.

2. In a trolley wire tap, a tubular handle forming fuse casing of insulation material, a conductive bushing fixed in one end of said casing and internally threaded, a conductive screw plug having an externally threaded inner end socket turned into said bushing and adapted to fit over one end of a fuse in said casing, said plug having an axial outer end stud on the other end of the socket, a hand guard of insulation material fitted

over said stud and seating on said other end of the socket, a conductive trolley wire engaging hook, means for detachably connecting said stud and hook in locked engaging relation and clamping said guard against said seat, and a conductive connector in said socket adapted to connect said end of the fuse with the bottom of the socket, said plug, guard and means being detachable from said casing as a unit by turning said socket out of said bushing by means of said hook and said connector being frictionally locked in said socket for removal with said plug and subsequent removal from the socket.
